[57] CLAIM

The ornamental design for a flexible disk drive, substantially as shown and described.

DESCRIPTION

FIG. 1 is a perspective view of a flexible disk drive showing the front, top and right side of our new design; FIG. 2 is a top plan view of the flexible disk drive shown in FIG. 1;

FIG. 3 is a left side elevation view of the flexible disk drive shown in FIG. 1;

FIG. 4 is a bottom plan view of the flexible disk drive shown in FIG. 1; and

FIG. 5 is a rear elevation view of the flexible disk drive shown in FIG. 1.
